UNITED STATES PATENT OFFICE.

ARTHUR V. A. McHARG, OF NEW YORK, N. Y., ASSIGNOR TO THOMAS E. MURRAY, OF NEW YORK, N. Y.

PROTECTIVE DEVICE FOR ELECTRIC CIRCUITS.

1,120,212.

Specification of Letters Patent.

Patented Dec. 8, 1914.

Application filed November 28, 1913. Serial No. 803,521.

To all whom it may concern:

Be it known that I, ARTHUR V. A. McHARG, a citizen of the United States, residing at New York, in the county of New York and State of New York, have invented a certain new and useful Improvement in Protective Devices for Electric Circuits, of which the following is a specification.

The invention is a protective device for electric circuits. It embodies a novel principle, namely, interrupting an electric circuit by destroying by heat electrically generated in said circuit, a body of destructible material, by means of which body terminals of said circuit are held in contact, and thereby permitting said terminals to separate and break said circuit. This principle may be embodied in many different forms of apparatus. I herein illustrate one practical and efficient form wherein a movable switch member normally retracted by a spring is held in circuit closing position against the resiliency of said spring by means of a fuse or stop of material destructible by heat, which stop is then in contact with a conductor mounted on said switch member and in circuit. Upon the development of an overload current on the circuit, said conductor becomes heated and in turn heats and so destroys the stop. The switch member then being released is retracted to open circuit by the spring. In this way, the circuit is protected from the effects of said overload current by a fuse or body of destructible material which is not in the circuit.

In the accompanying drawings—Figure 1 is a longitudinal section of my protective device on the line x, x of Fig. 2. Fig. 2 is a horizontal section on the line y, y of Fig. 1. Fig. 3 is an elevation of the bridge-carrying extremity of the switch lever. Fig. 4 is a modified form of the destructible stop or fuse.

Similar numbers of reference indicate like parts.

1 is a base of insulating material, 2 is a switch lever also of insulating material. Upon the upper side of said lever is a metal plate 3, integral with which are lateral side pieces 4 which are bent over and receive the body of the switch lever between them. The lever is supported on a shaft 5 of insulating material journaled in plates 6 secured to the base 1, with which plates the side pieces 4 make contact. On the under side of lever 1

near the end thereof is a stirrup-shaped plate 7. When the lever is in circuit-closing position, as shown in Fig. 1, the plate 7 enters between the arms of a contact clip 8 secured to base 1. Extending outwardly from the end of lever 2 is a bridge conductor 9 in loop form. One end of said conductor is in electrical contact with plate 3. The other end is in electrical contact with the front edges of plate 7, said end being widened to extend across said edges and being secured in place by the screw 10 entering lever 2, as shown in Fig. 3.

11 is a standard having a threaded recess in its upper end to receive the head of screw 12, which enters base 1. Between the shank of screw 12 and standard 11 is a clearance so that said standard may freely turn on said shank. The recess in standard 11 is interiorly threaded to receive the screw 75 plug 13 which is on the end of an insulating rod 14. Rod 14 has a flange 15 and at its upper end a head 16 by which it can be rotated. The standard 11 supports a toothed disk 17 of fusible metal or other material destructible by heat, which disk has a central opening to receive the plug 13, so that when the plug is in place, the disk is clamped between the flange 15 and the top of standard 11.

On the switch lever 2 is an upwardly extending arm 18, to which is attached one end of the helical retracting spring 19, the other end of said spring being secured to base 1. Circuit wires 21, 20 are respectively connected to plates 6 and clip 8.

A box-shaped cover 22 is provided having an opening for the passage of the head 16 and a slot in one of its walls and extending to the edge thereof for the admission of shaft 5. This slot is closed when the cover is in place by a plate 23 secured on the base 1 and provided on its upper edge with a semicircular recess receiving shaft 5. A handle 25 is secured on the end of shaft 5 which projects outside of the cover.

The operation is as follows: The cover being preferably removed, the screw plug 13 is withdrawn from the standard 11, the disk 17 is put in place on said standard, and the plug 13 is reinserted to clamp the disk 17 firmly between the standard and flange 15. The lever 2 is then brought into circuit closing position, the bridge 9 passing through one of the spaces between the projections on 110

the disk. The lever being retained in this position by the operator, the head 16 is rotated until one of said projections 24 comes directly above the bridge 9. The lever is 5 then released, but is held from rising under the pull of spring 19 by the projection 24 with which the bridge 9 becomes held in contact. The bridge 9 is to be so proportioned as that it will conduct a predetermined 10 normal current without becoming hot enough to fuse or destroy the holding projection, but to become heated to a sufficient degree to destroy said projection upon the occurrence of any selected overload current. 15 To this end, it may be made of higher resistance than the rest of the circuit. The destruction of said holding projection then releases lever 2 which is immediately thrown up, as indicated in dotted lines, Fig. 1, out 20 of clip 8 by the action of spring 19, thus breaking the circuit and so protecting any devices therein included from the effects of said increased current.

In order to reset the apparatus, the disk 25 17 is rotated by head 16 until another projection on said disk comes into position to engage bridge 9, and obviously the resetting may be repeated as many times as there are 30 projections on said disk. When all of said projections have in turn been destroyed, a new disk is to be substituted.

Instead of making the disk 17 of destructible material, I may make only the portions thereof which engage the bridge 9 of said 35 material, and this can be done in various ways. One way is illustrated in Fig. 4. Here the disk 17 may be constructed of any material, preferably insulating and refractory, serving as a support for wires 26 of 40 fusible material which extend between the projections on said disk and are secured thereto. The disk is set so that one of said wires comes directly over the bridge 9, and acts as a stop to prevent retraction of the 45 lever by spring 19. This wire on the occurrence of an overload current becomes fused, releasing the lever, as already described.

I claim:

1. A fixed circuit terminal, a movable circuit terminal coöperating therewith, resilient retracting means for said movable terminal, a plurality of devices for holding

said movable terminal in predetermined position with reference to said fixed terminal against the resiliency of said retracting means, means for moving said devices successively into engagement with said movable terminal, and means for heating said devices to destroy the same to release said movable terminal. 60

2. A fixed circuit terminal, a movable circuit terminal coöperating therewith, resilient retracting means for said movable terminal, a plurality of stops for holding said movable terminal in predetermined position 65 with reference to said fixed terminal against the resiliency of said retracting means, means for moving said stops successively into engagement with said movable terminal, and means controlled by an overload 70 current on said circuit for destroying said stops.

3. A movable switch member divided into two mutually insulated sections, resilient retracting means therefor, a bridge of conducting material of higher resistance than said sections and connecting said sections, and means in contact with said bridge for holding said member in circuit closing position against the resiliency of said spring; 80 the said holding means, upon the heating of said bridge by current on said circuit, being destructible to release said movable member to open said switch. 75

4. A movable switch member divided into 85 two mutually insulated sections, resilient retracting means therefor, a bridge of conducting material of higher resistance than said sections connecting said sections and projecting from said switch member, and a 90 stop in contact with said bridge for holding said member in circuit closing position against the resiliency of said spring; the said stop, upon the heating of said bridge by current on said circuit, being fusible to 95 release said movable member to open said switch.

In testimony whereof I have affixed my signature in presence of two witnesses.

ARTHUR V. A. McHARG.
